UNITED STATES PATENT OFFICE.

ARTHUR H. BLACKBURN, OF WORCESTER, MASSACHUSETTS, AND SAMUEL A. ARMSTRONG, OF DETROIT, MICHIGAN, ASSIGNEES, BY MESNE ASSIGNMENTS, TO RILEY STOKER CORPORATION, OF WORCESTER, MASSACHUSETTS, A CORPORATION OF MASSACHUSETTS.

UNDERFEED STOKER.

Application filed April 9, 1923. Serial No. 630,990.

To all whom it may concern:

Be it known that we, ARTHUR H. BLACKBURN and SAMUEL A. ARMSTRONG, subjects of the King of Great Britain, residing, respectively, at Worcester, in the county of Worcester and State of Massachusetts, and at Detroit, in the county of Wayne and State of Michigan, have invented certain new and useful Improvements in Underfeed Stokers, 10 of which the following is a specification.

Our invention relates to improvements in underfeed stokers and more particularly to heavy duty stokers, in which the coal consumption rate must be high and the quantity 15 of coal handled may be large in relation to the stoker area.

It is now known practice to construct a stoker wherein a plurality of parallel retorts, known as lateral retorts, are arranged at 20 right angles to a longitudinal main retort, to receive their fuel supply from the main retort, the main retort only being equipped with a ram or other suitable means for the introduction of fuel from the fuel hopper, 25 the distribution of fuel from such hopper through the area served by the lateral retort affording a relatively large fire-bed.

One of the objects of our invention is to provide a lateral retort stoker for heavy 30 duty, wherein the amount of fuel handled may be large, and the introduction and distribution thereof may be advantageously effected in such a way as to involve only minimum tendency of the fuel to mass, choke, 35 bridge, or form clinkers, in any way to militate against efficient combustion; and at the same time to improve the feeding action and combustion characteristics and air distribution for heavy service.

40 These and further objects which will become apparent to those skilled in the art from the following description, taken in conjunction with the accompanying drawings, we attain by the construction hereinafter 45 pointed out and claimed, but it will be understood that while we have illustrated in the drawings for the purposes of disclosure only a single embodiment of our invention, changes in many matters of construction and 50 arrangement may be made without departure from the spirit of our invention within the scope of the appended claims.

In the drawings, Fig. 1 is a transverse vertical section through a stoker embodying

our invention, taken on line 1—1 of Fig. 2; 55 Fig. 2 is a plan view, with parts broken away; Fig. 3 is a longitudinal vertical section on line 3—3 of Fig. 2; and Fig. 4 is a fragmentary view of the furnace front.

In our improved stoker we provide a plurality of longitudinally extending main retorts having a central group, each of these main retorts having independent fuel-supply mechanism, so that, as between these main retorts a very large quantity of fuel may be 60 handled while maintaining relatively small capacity of each retort and consequent low demand on the feeding and distributing mechanism appurtenant thereto, thus to prevent expensive and otherwise undesirable 65 enlargement of the equipment unit, and to prevent stoppage or breaking of one fuel feeding mechanism from putting the entire furnace out of commission. The longitudinal 70 retorts of this central group are arranged 75 with their adjoining margins somewhat spaced apart for air passage therebetween, and tuyere structures span between adjoining margins of such retorts, to supply air toward both of the adjoining retorts. 80 Flanking the extreme ones of the longitudinal 85 main retorts are two groups of lateral retorts, each group comprising a plurality of retorts, tuyere-equipped at their margins, having their receptive ends arranged to receive fuel from the respective extreme main retorts, and preferably having their mouths laterally down-sloping toward dump structures extending along the sides of the firebox floor. 90

In the exemplification shown 10 and 10' indicate hoppers for the green fuel, from which coal may be fed by rams 11 and 11', independently operable, through the feed throats 12 and 12' into two parallel longitudinal main retorts 13 and 13' which are preferably arranged with their mouths in a horizontal plane and which have their contiguous side walls 14 and 14' somewhat spaced apart to form an air trunk 15 therebetween to feed air through the lateral openings of the tuyere structure 16 surmounting, and spanning between, the upper margins of said walls 14 and 14'. 95

The lateral retorts 18 and 18' are arranged in two respective groups flanking the extreme or outer walls of the main retort, each such group comprising a plurality of 100

retorts arranged side by side and extending generally transversely with respect to the line of the main retort, with the side walls of adjoining lateral retorts spaced apart to 5 form air trunks 19 surmounted by the laterally extending tuyère structures 20 and 20'. In general, all parts associated with the side of the furnace fed from hopper 10 are duplicated on the side of the furnace fed 10 from hopper 10', the parts on the latter side being designated by the same numerals as the like parts on the first-mentioned side, but differentiated by the exponent prime.

The arrangement determining the condition of fuel passing from a main retort into lateral retorts supplied therefrom, may be varied, but for some purposes it is preferable to form in the outer wall of each extreme main retort side-openings 21 between 15 side-posts 22, and to arrange the receiving ends of the respective lateral retorts to communicate directly with the respective main retorts through these openings. The tuyère-margined mouths of the lateral retorts 18 20 preferably lie in a plane downsloping somewhat from the level of the main retort tuyères to the delivery end of the lateral retorts, and the bottoms 24 of the lateral retorts are preferably each formed with an up-sloping 25 delivery end portion 25 and a flat receiving end 26, horizontally disposed. The bottoms of the lateral retorts at the receiving end, are preferably lower than the flat bottom 27 of the main retort which supplies fuel 30 thereto, and the lateral retort bottoms find 35 effective continuation in channels 28 formed in or below the main-retort bottom.

Fuel-distribution means are preferably provided in each lateral retort, and with 40 lateral retorts of the two opposite groups arranged in aligning pairs, the distribution means for the two opposed retorts of such a pair may be united for operation in common. Thus, 29 represents pusher blocks in 45 lateral retorts 18, arranged in the flat bottom portions of the latter and connected by bar portions 30 with corresponding blocks 29' in the respective retorts 18', such bars extending through the channels 28 aforesaid and through apertures opening into the wind-trunk 15 but substantially filled by the 50 bars. Each said bar may be reciprocated by connection of its depending finger 31, through a link 32 with a corresponding rocking lever 33 on a rock shaft 34 that extends longitudinally of the structure and through the furnace front for exterior operation by a suitable crank 35, which may be operated by a prime mover 36 independently of or in 55 timed relation to the operations of the feeding rams.

Fuel distributing means are preferably provided also in the main longitudinal retort to further the feeding action of the supply ram, such distributing means being 60

shown as flat plates 37 running along the main retort bottom, each provided with one or more pusher blocks 38 and each connected to its respective ram by a lost motion connection shown as involving adjustable stop pins 39 between which there works the ram-arm 40 to reciprocate the feed plate with a varying degree of lost motion.

The fire-box floor may be completed by 65 end-plate structures 41 and 41' flanking the delivery ends of the lateral retort group and down-sloping to the dump platforms 42, 42' which extend substantially to the respective furnace side walls 43 and 43', thus separating the combustion space 44 above the 70 floor from the space below the floor which is divided into lateral ash pits 45, 45' and its central wind-box 46, to which air chamber air under pressure is supplied from any suitable means not shown. The partition 75 separating the wind-chamber and ash pits may comprise partition plates 48, between which there span the cross-beams 49 which centrally support the retort structure, the 80 margins of the lateral retorts being carried on longitudinal stringers 50. These plates 48 may also support the rock shafts 51 and 51', extending through the front of the furnace for manual operation, and upon which the dump platforms 42, 42' are mounted. 85 Adjacent the front wall 53 and the bridge wall 54, high, deeply sloped tuyères 55 may be employed at the extreme margins of the lateral retort group to prevent clinkering 90 and maintain freedom of distributive feed. 95

In operation, it will be observed, the quantity of coal handled may be very large, without unduly loading either feed mechanism, and while maintaining the coal in relatively small bodies in cross-sectional area in all 100 portions of the stoker, so as to prevent or minimize packing, bridging, and lumping of the coal. Throughout all of the areas distributive feeding tends strongly to prevent the formation of surface clinkers detrimental to the adequate passage of air through the fuel in combustion, and the provision of independently operable feeding devices for the plurality of main retorts admits of 105 selective operation, so that the feed rams and their associated distributing means to the main retorts, may be operated either simultaneously or nonsimultaneously, with quite different effects as to the lifting and 110 breaking of the central mass of combustibles spanning over the central, uninterrupted tuyère wall 16.

We claim:

1. In an underfeed stoker, the combination of a plurality of longitudinal main retorts forming a central group, spaced apart and having tuyère structures spanning their adjoining margins, and two groups of laterally-extending retorts flanking the extreme ones of said central retorts, each said 115

- laterally extending retort communicating with the adjacent one of said central retorts below the level of said tuyère structures to receive from such central retort fuel not yet in state of combustion, said laterally-extending retorts respectively having marginal tuyères, means for feeding fuel longitudinally along said longitudinal main retorts and means, below the level of said tuyères, for feeding fuel not yet in combustion laterally along said laterally extending retorts.
2. In an underfeed stoker, the combination of a plurality of longitudinal main retorts forming a central group, these being spaced apart and having tuyère structures spanning their adjoining margins, two groups laterally extending retorts flanking the extreme ones of said central retorts and arranged to receive fuel therefrom, and independent means for introducing fuel into each of the said extreme longitudinal retorts.
3. In an underfeed stoker, the combination of a plurality of longitudinal main retorts forming a central group, spaced apart and having tuyère structures spanning their adjoining margins in uninterrupted line, the extreme side walls of said group of longitudinal tuyères having lateral openings therethrough, and two groups of laterally extending retorts, each group comprising a plurality of retorts spaced apart and having tuyère structures spanning between their adjoining margins and at their receptive ends opening through the respective side openings of said extreme longitudinal retorts, to receive fuel therefrom, and independent means for introducing fuel into each of said extreme longitudinal retorts.
4. In an underfeed stoker, the combination of two longitudinal main retorts arranged in substantial parallelism with their mouths substantially horizontal and with their adjoining side walls spaced apart to provide an air passage therebetween, tuyère structures mounted on the adjoining margins of said main retorts, and two groups of laterally extending retorts each group comprising a plurality of such retorts arranged with their mouths down-sloping away from the main retort and with their side walls spaced apart to provide air passages therebetween, and tuyère structures mounted on the adjoining margins of said lateral retorts, the inner or receiving ends of the lateral retorts of each group being arranged to receive fuel from the adjoining one of said longitudinal retorts, independent means for feeding fuel to each said longitudinal retort, and fuel-distributing means in each said lateral retort.
5. In an underfeed a stoker, the combination of two longitudinal main retorts arranged in substantial parallelism with their mouths substantially horizontal and with their adjoining side walls spaced apart to provide an air passage therebetween, tuyère structures mounted on the adjoining margins of said main retorts, and two groups of laterally extending retorts each group comprising a plurality of such retorts arranged with their mouths down-sloping away from the main retort and with their side walls spaced apart to provide air passages therebetween, and tuyère structures mounted on the adjoining margins of said lateral retorts, the inner or receiving ends of the lateral retorts of each group being arranged to receive fuel from the adjoining one of said longitudinal retorts, and independent means for feeding fuel to each said longitudinal retort.

ARTHUR H. BLACKBURN.
SAMUEL A. ARMSTRONG.
